UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE FOR BOILERS.

Application filed November 2, 1921. Serial No. 512,294.

To all whom it may concern:

Be it known that I, ETHAN I. Dodds, a citizen of the United States, and a resident of Pittsburgh, in the county of Allegheny and State of Pennsylvania, have invented 5 certain new and useful Improvements in Stay-Bolt Structures for Boilers; and I do hereby declare the following to be a full, clear, and exact description of the invention, 10 such as will enable others skilled in the art to which it appertains to make and use the same.

This invention relates to improvements in staybolt structures for boilers,—one object 15 of the invention being to provide simple and efficient bearing and closure devices for stay-bolt structures which may be quickly applied to a boiler sheet.

A further object is to so construct a two- 20 part bearing member and a bolt head that the former may be effectually held in position against outward movement, by the boiler sheet, and sustained against inward movement by co-operation of the cap or closure 25 on said bearing member, with the outer face of the boiler sheet.

With these and other objects in view, the invention consists in certain novel features of construction and combinations of parts as 30 hereinafter set forth and pointed out in the claims.

In the accompanying drawings, Figures 1 and 2 are sectional views taken at right angles to each other and illustrating an embodiment of my invention. Figure 3 is a plan view of the two-part bearing member, and Figure 4 is an end view showing the bolt head.

The outer sheet of a boiler is represented 40 at 1 and provided with a cylindrical hole 2 for the accommodation of the bearing devices and bolt head mounted therein as more specifically hereinafter described.

The bearing member for the bolt head 45 comprises two members 3—3 each of which is formed with a partial rounded bearing face 4 for the rounded portion of the head 5 of a staybolt 6. The bolt head 5 is formed with a transverse, wedge-shaped recess 7 and 50 the respective members of the bearing sleeve are provided with inwardly projecting arms 8 which, when the bearing sleeve is assem-

bled, abut against each other as shown in Figures 1 and 3, and said arms are provided with wedge-shaped depending portions 8^a 55 which enter the wedge-shaped recess in the bolt. The said wedge-shaped recess 7 in the bolt may extend downwardly (as seen in Figure 2) below the head of the bolt and said recess has such proportions relatively 60 to the wedge-shaped depending portions 8^a of the bearing sleeve members that said bolt head may have sufficient freedom of movement when in use without hindrance from said wedge-shaped portions 8^a. 65

Each member of the bearing sleeve extends inwardly beyond the inner face of the boiler sheet and is provided with a flange 9 which underlies said inner face and the sleeve members are thus prevented from outward movement. The outer ends of the sleeve members project beyond the outer face of the boiler sheet and are threaded externally as indicated at 10 to receive the internally threaded portion of a cap or closure 11. The edge of the closure 11 is co-operable with the boiler sheet to sustain any pulling strain which might be brought to bear by the bolt on the bearing sleeve and between said edge of the cap or closure and 75 the outer face of the boiler sheet, a washer 12 may be interposed. 80

Having fully described my invention what I claim as new and desire to secure by Letters Patent, is:

1. In a staybolt structure, the combination with a boiler sheet having an opening, of a two part bearing member passing through said opening and adapted to engage the inner face of the boiler sheet, the outer ends 85 of the parts of said bearing member projecting beyond the outer face of the boiler sheet and threaded externally, a cap or closure threaded on said bearing member and cooperable with the boiler sheet, and stay bolt having a head mounted within the parts 90 of said two-part bearing member.

2. In a staybolt structure, the combination with a boiler sheet having an opening, of a bearing member passing through said opening, said bearing member comprising two parts cooperable with the inner face of the boiler sheet, a cap or closure threaded on the two-part bearing member and cooperable 95 100

with the boiler sheet, a staybolt having a head mounted in the parts of said two-part bearing member and having a transverse recess, arms projecting inwardly from the 5 respective parts of the bearing member, and parts depending from said arms and entering the transverse recess in the bolt and smaller in size than said recess whereby the

bolt head is permitted to have freedom of movement in the bearing member.

In testimony whereof, I have signed this specification in the presence of a subscribing witness.

ETHAN I. DODDS.

Witness:

EDWIN S. RYCE.
